E. L. CLARK

PRESSURE RETAINING VALVE

Original Filed March 4, 1922

12 Inventor
Eddy L. Clark
by his Attorney
John R. Nease

UNITED STATES PATENT OFFICE.

EDDY L. CLARK, OF WEST PITTSTON, PENNSYLVANIA.

PRESSURE-RETAINING VALVE.

Application filed March 4, 1922, Serial No. 541,082. Renewed October 24, 1924.

To all whom it may concern:

Be it known that I, EDDY L. CLARK, a citizen of the United States, and resident of West Pittston, in the county of Luzerne and State of Pennsylvania, have invented certain new and useful Improvements in Pressure-Retaining Valves, of which the following is a specification.

This invention relates to pressure retaining valves, and particularly valves of the kind used in connection with the air brake systems of railroad cars.

The object of my invention is to provide a pressure retaining valve of simple and efficient construction having a valve element that can be readily mounted within the valve case and adjusted to resist any required pressure from the brake cylinder; such a valve that will effectually maintain its seat under the varying conditions of service; and such a valve wherein the elements are readily removable and replaceable as occasion may require.

With these and other objects in view my invention comprises various novel features of construction and combinations of parts which will be hereinafter described and claimed.

In the drawings:

Fig. 1 is a vertical section of a valve device embodying one form of my invention.

Fig. 2 is a similar section at right angles to Fig. 1, the valve element being shown in elevation.

Fig. 3 is a transverse section of the device, as on the line 3—3 of Fig. 2, showing a supporting bar therefor.

Fig. 4 is a vertical section, on a smaller scale, of a modified form of valve element.

Referring to the drawings, 10 designates a body having a central port 11 provided intermediate its ends with a lateral exhaust port 12. The lower end of the body is adapted to be coupled, as usual, to the train pipe extending from the brake cylinder. Fitted to the upper end of the body is a valve case 13 such end constituting the bottom of the valve chamber and having a suitably-disposed vent port 14. Rotatably fitted within the body is a transverse cock key 15 manually operable to establish communication between the train pipe and the exhaust port 12, or between the train pipe

and the vented chamber of the valve case, as desired. Within this chamber is mounted the valve element which normally closes communication between the said chamber and the port 11, but is adapted to be automatically raised to open position by a predetermined pressure in the brake cylinder. 55 60

According to the preferred form of my invention, the valve element comprises a cylindrical support composed of two members 16 placed face to face and in axial alignment with each other, and so connected that they can be nicely adjusted within limits toward and from each other. In the present instance the adjustable connection between the members is attained by providing one of the members with a threaded male 70 portion 17 and the other member with a tapped female portion 18 to receive the portion 17, the latter member having a radial set-screw 19 whereby when the members are adjusted by their relative rotation they can 75 be tightly secured in the position of adjustment. On the outer faces of the members 16 are secured the flat surfaces of two plano-convex bodies 20, 21, respectively, of elastic substance, such, for example, as rubber. The flat surfaces of the two bodies are preferably firmly yet detachably secured to the respective members, and to that end I provide such surfaces with tapering or dove-tailed projections 22 which can be 80 85 readily fitted into and interlocked with correspondingly tapering sockets 23 in the respective members.

The pressure valve element thus constructed is so disposed within the valve 90 chamber that one of the bodies, as 20, rests on a concave valve seat 24 at the bottom of the chamber, and the other body, as 21, bears yieldingly against a concave bearing surface 25 at the top of the chamber in such 95 a manner as to press the valve element bodily downward and hold the lower member positively down to its seat in opposition to the upward pressure from the brake cylinder. 100

Preferably the bearing surface 25 is formed on a head 26 which is vertically adjustable within the upper portion of the chamber in a manner to exert more or less pressure on the opposing body as desired. 105 This head is provided with an upstanding

threaded shank 27 which is adjustably fitted to a threaded orifice 28 in the top of the case. A lock screw 29 fitted into the orifice bears upon the top of the screw-shank.

5 It will be seen that the two members of the metal support can be readily adjusted to vary the spaced relation of the bodies 20, 21 to each other in accordance with the depth of the valve chamber, and that when 10 the valve element is introduced in the chamber the screw-shank can be vertically adjusted to effect a predetermined pressure of the lower or closing body upon the valve seat at the bottom of the case. Also that 15 the valve element when it is positioned within the case will be firmly held upon the seat under varying conditions of service; that is, the valve will be effectually seated not only when the flow of air thereto is 20 turned off, but when the valve is subjected to severe vibrations, or is set at various angles. It will also be seen that the novel valve element can be mounted with either end body thereof imposed on the seat 24, and 25 that the parts of the device are readily removable and replaceable, as necessity may require.

I preferably provide the body 10 with a tapering dovetail projection 30 adapted to 30 be seated and held in a correspondingly formed socket 31 in a bracket bar 32 bolted to the side of the car, &c., to which the retaining valve device is applied.

In Fig. 4 of the drawings I have illustrated a modified form of valve element wherein the support comprises a single hollow cylinder 16' having therein elastic bodies 20, 21 with rounded outer ends which project beyond the respective ends of the 40 cylinder.

It is to be understood that I do not limit my invention to the details of construction herein disclosed, as the parts may be modified within the principle of the invention and the scope of the appended claims.

I claim:

1. The combination with a valve casing having a port at one end thereof, of a valve element comprising a support movably contained in said casing, an elastic body carried by and projecting from said support, the projecting portion of the body being convex and being adapted to be seated on the port, and adjustable pressure means acting upon the valve element to maintain the said body normally seated on the port.

2. The combination with a valve casing having a port at one end thereof, of a valve element comprising a support movably contained in said casing and two oppositely disposed elastic bodies carried by said support, one of said bodies having a projecting convex surface adapted to be seated on the port, and a pressure member adjustably

mounted in the end of the casing remote from the port and adapted to bear upon the other elastic body.

3. The combination with a valve casing having at one end thereof a port and at the other end a bearing surface, of a valve element comprising a cylindrical support, elastic bodies having convex surfaces projecting beyond the respective ends of said support and arranged to press in opposition to each other against the mouth of the port and the said bearing surface, and means whereby the opposing pressure of the said bodies can be regulated.

4. The combination with a valve casing having at one end thereof a port with a valve seat, a bearing head at the opposite end of the casing and means whereby said head can be adjusted toward and from the valve seat, of a valve element interposed between the valve seat and the head, said element comprising a cylindrical support, and convex bodies carried by and projecting from the ends of said support, one of said bodies being imposed upon the valve seat and the other bearing against the head.

5. The combination with a valve casing having at one end a port with a valve seat, a bearing head at the opposite end of the casing, and means whereby said head can be adjusted toward and from the valve seat, of a valve element comprising two associated supporting parts, means whereby said parts can be adjusted toward and from each other, bodies secured to the respective supporting parts and having convex outer ends arranged to press in opposition to each other against the valve seat and the upper bearing surface.

6. In a pressure retaining valve, a valve element comprising two associated supporting parts, means whereby said parts can be adjusted toward and from each other, a closure member on one of said parts, and a cushioning member on the other part.

7. In a pressure retaining valve, a valve element comprising two associated supporting parts, means whereby said parts can be adjusted toward and from each other, and bodies of elastic substance having convex surfaces projecting beyond the outer ends of said supporting parts.

8. In a pressure retaining valve, a valve element comprising two supporting parts having a male and female screw connection, means for securing said parts in positions of relative adjustment, and bodies of elastic substance detachably secured to the respective supporting parts, and having convex surfaces projecting beyond the respective outer ends of said parts.

9. In a pressure retaining valve, a valve element comprising two supporting parts, means whereby said parts can be adjusted

toward and from each other, and plano-convex bodies of elastic substance on the outer surfaces of the respective supporting parts, said bodies and surfaces having interlocking dove-tail connections.

5. 10. In a pressure retaining valve, a valve element comprising two supporting parts having a male and female screw connection, means for securing said parts in posi-

tions of adjustment, plano-convex bodies of 10 elastic substance on the outer surfaces of the respective supporting parts, said bodies and surfaces having interlocking dove-tail connections.

Signed at West Pittston, in the county 15 of Luzerne and State of Pennsylvania this 28th day of February A. D. 1922.

EDDY L. CLARK.
